UNITED STATES PATENT OFFICE.

ARNOLD J. SHARY AND THOMAS L. ANTHONY, OF WILBER, NEBRASKA.

WINDMILL ATTACHMENT.

No. 817,808.

Specification of Letters Patent.

Patented April 17, 1906.

Application filed November 7, 1905. Serial No. 286,231.

To all whom it may concern:

Be it known that we, ARNOLD J. SHARY and THOMAS L. ANTHONY, citizens of the United States, residing at Wilber, in the 5 county of Saline and State of Nebraska, have invented certain new and useful Improvements in Windmill Attachments, of which the following is a specification.

This invention relates to improvements in 10 means for transmitting power from a vertically-reciprocating windmill pump-rod to a churn, washing-machine, or other device which can be suitably driven by such means.

The primary object of our improvements 15 is to provide inexpensive means which can be easily erected by unskilled labor and which can be adapted by simple adjustments to the varying strokes of the dashers of different makes and sizes of churns or the movements of 20 the handles or drive-wheels of different styles of washing-machines.

A further object is to provide an attachment that can be quickly and easily thrown out of operative connection.

25 Other objects of general utility will be apparent from an examination of our invention as hereinafter disclosed.

In the accompanying drawings, which form 30 a part of this application, Figure 1 shows in side elevation one application of our invention in an approved form. Fig. 2 shows a slightly-modified form of a portion of the transmitting elements. Figs. 3 and 4 are fragmentary details of portions of the apparatus shown in the other views. Fig. 5 is a 35 cross-section through the churn-handle shown in Fig. 2.

Referring to the parts of the apparatus as disclosed in the drawings, A represents a portion 40 of an ordinary windmill pump-rod to which a bracket-casting a' is bolted.

A' represents an upright piece bolted to the cross-bars of the windmill-tower.

D is a post which is erected at a convenient 45 distance from the tower.

Mounted on the upright A' and the post are pulleys b', on which are run a wire or cable B, the ends of which are secured to the bracket a'. From the post an arm d' extends horizontally, and same is supported by 50 a brace d'', secured thereto and to the post. On the outer end of the arm d' are rotatably mounted two disks C, through which are formed a plurality of holes c', which register, 55 so that by inserting a pin or bolt therethrough

the disks may be locked together. Bolted loosely to one of the disks is a lever c', in which several holes are provided to receive a bolt which pivotally connects the lever to the arm d'. To the other end of the lever the 60 cable B is connected. To the other disk a lever c'' is secured by a bolt passing through one of the holes c''. The lever c'' has a series of holes c''' near its outer end, and through one of these passes a bolt which loosely connects 65 one end of a link c'' to said lever. As shown in Fig. 1, the link c'' is loosely bolted to the handle e' of the churn E by a bolt passing through one of the holes c''. As shown in Fig. 2, the link is connected to the dasher f' 70 of a churn F by a collar f'', which is connected with the link by a bolt passing through one of the holes c''. This collar has a setscrew by which its connection with the dasher may be adjusted and which also permits the ready removal of the collar from the dasher.

It will be apparent that the openings d' in the arm d', c' in the lever c', c'' in the disk C, C''' in the lever c'', and c'' in the link c'' afford a 80 wide range of adjustability, so that the apparatus can be readily adapted to various uses and objects.

The reciprocation of the pump-rod will, through its connection with the cable B, 85 cause the lever c' to rock on its pivot-bearing on the arm d', and this will produce an oscillation of the disk C, to which the lever is connected by a bolt passing through a slot in its outer end. When the disk thus operated is 90 bolted to its companion disk, the lever c'' will be oscillated and communicate its motion to the link c'', which in turn will drive the handle or dasher as described.

Having thus described our invention, what 95 we claim as new, and desire to secure by Letters Patent, is—

1. In a power-transmitting apparatus, a reciprocating rod, supports erected adjacent to said rod, pulleys mounted on said supports, 100 a cable arranged on said pulleys and connected with said rod, disks mounted on one of said supports and having registering openings therein, a pivoted lever connected with one of said disks and to said cable, a lever 105 connected to the other disk, means for locking said disks together, and means for connecting said lever to the object to be driven.

2. In a power-transmitting apparatus, in combination with a reciprocating rod, sup- 110

ports erected adjacent to said rod, pulleys mounted on said supports, a cable arranged on said pulleys and connected with said rod, disks mounted on a suitable support and having a series of registering openings therein, a lever adjustably pivoted on a support and connected with one of said disks, a lever connected with the other disk and having a plurality of openings therein, and adjustable

means for connecting said second lever to the object to be driven.

In testimony whereof we affix our signatures in presence of two witnesses.

ARNOLD J. SHARY.
THOMAS L. ANTHONY.
